UNITED STATES PATENT OFFICE.

HOWARD J. MURPHY, OF READING, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING APPARATUS.

Application filed March 14, 1922. Serial No. 543,648.

This invention pertains to lubricating apparatus. It is among the objects of the invention to provide improved apparatus for delivering lubricant under pressure from a lubricant-expelling device to a lubricant-receiving part.

In the drawings, which show a preferred form of one embodiment of my invention:—

Figure 1 is a side elevation of a lubricant-expelling gun coupled to a lubricant-receiving nipple;

Fig. 2 is a section on the line 2—2 of Fig. 1, being partly in elevation;

Fig. 3 is a section on the line 3—3 of Fig. 2, showing the discharge end of the device in section and showing the lubricant-receiving nipple in elevation;

Fig. 4 is a view similar to Fig. 3, showing the relative position of the parts prior to completion of the coupling operation and showing portions of the coupling apparatus in elevation;

Fig. 5 is a view similar to Fig. 4, but showing the relative position of the parts pursuant to the coupling operation;

Fig. 6 is a view showing the parts in the position illustrated in Fig. 5, the section being taken on a different line, viz., the line 6—6 of Fig. 2;

Fig. 7 shows side and end elevations of the preferred form of sealing part shown in section in Fig. 3;

Fig. 8 is an elevation of a preferred form of sealing washer;

Fig. 9 is an elevation of a preferred form of valve part; and

Fig. 10 shows an end elevation and central longitudinal section, partly in elevation, of the preferred form of lubricant-receiving nipple.

Referring to the drawings and to the preferred form of my invention selected for illustrative purposes, I have shown a lubricant-expelling device taking the form of the usual grease gun including the barrel 11, and the rear head 12, into which is threaded a stem 13 carrying the usual piston, not shown. The pressure may be exerted on the contents of the barrel 11 by turning the stem 13 relative to the barrel 11 in clockwise direction, as viewed from the right of Fig. 1. The expelling device illustrated is provided with a front head 14 carrying coupling means and valve means, the coupling

means being adapted to engage the lubricant-receiving nipple 15 which, as best viewed in Fig. 10, may be provided with a receiving opening 16 and lateral projections 17, herein shown as four in number, and integral with the body of the nipple. The nipple may be provided with the usual check valve 18 held to its seat by a spring 19. The preferred form of coupling means illustrated may include a part 20 presenting an opening in the end thereof adapted to fit over the projections 17 and to receive within it a portion of the nipple 15, the part 20 providing interior flanged surfaces 21 adapted to underlie the projections 17 on the nipple when the part 20 is turned relative to the nipple.

Within the part 20, and rotatable relative thereto, is shown a sealing part 24 carrying a sealing washer 25 and presenting extensions 26 adapted to bear against the sides 75 of the nipple adjacent the projections thereon so as to oppose rotation between the nipple 15 and sealing part 24 during the coupling operation. The sealing part 24 is apertured at 27 to admit passage of lubricant therethrough and is slotted across the top at 28 to permit passage of lubricant thereto when the valve means is open. The preferred form of valve means illustrated is rotary in form, comprising the apertured 80 disc 30 having a projection 31 entering a slot 32 in a part rotatable relative to the sealing part 24, the slot as herein illustrated being in the coupled part 20.

To effect a tight joint, I have provided 90 cooperating pin and slot means for effecting approaching movement between the interior flanged surfaces 21 and the sealing part 24, which in the embodiment of my invention illustrated comprises cooperating pin and 95 slot means interposed between the sealing part 24 and the part 20. As illustrated, the slot 40 is in the part 20 and the pin or screw 41 is in the sealing part 24.

Assuming the nipple to be disengaged 100 from the lubricant-expelling means, it is first entered in the nozzle until the position illustrated in Fig. 4 is reached, after which turning of the nozzle relative to the nipple brings the lateral extensions on the nipple over the 105 flanges 21 on the nozzle and at the same time the firm grip on the nipple is attained and a tight joint adjacent the lubricant-receiving

end thereof is effected by reason of the pressing of the sealing washer carried by the sealing part 24 against the top of the nipple as the sealing washer is moved to the left or as 5 the flanges 21 are moved to the right as viewed in Figs. 3 through 6 of the drawings. It will be understood that the sealing part cannot turn any substantial amount relative to the nipple during this coupling operation, 10 because of the projecting portions 26 engaging the lateral faces of the nipple. During this coupling operation, the valve is moving toward its open position and is opened substantially at the same time that the seal is 15 effected. During the grease expelling operation, any torque on the stem 13 in grease-expelling direction tends to tighten the coupling.

To prevent leakage around the sealing part 24, I have provided packing means typified by the cup washer 43 (Figs. 3 and 20 8) to seal the joint. The pressure of the lubricant against the valve disc 30 tends to keep it tightly seated against the sealing 25 part 24 with which it is adapted to reciprocate.

While I have shown and described a preferred form of one embodiment of my invention, it will be understood that changes involving omission, substitution, alteration 30 and reversal of parts, and even changes in the mode of operation, may be made without departing from the scope of my invention, which is best defined in the following claims.

35 I claim—

1. Lubricating apparatus including a lubricant-delivering nozzle presenting means for engagement beneath projections on a lubricant-receiving nipple, and a sealing part 40 movable relative to said means toward the nipple to seal the joint around a lubricant-receiving opening in the nipple, and cooperating pin and inclined slot means for positively effecting such movement, said 45 sealing part having means for engaging the nipple to prevent rotation of said sealing part relative to the nipple during coupling.

2. Lubricating apparatus including a lubricant-expelling device presenting a barrel

and a nozzle presenting an opening in its end to receive lateral projections on a lubricant-receiving nipple, a part inside said nozzle presenting portions engaging the projections when entered in said nozzle to oppose rotation of said part with said nozzle 55 relative to the nipple, and inclined pin and slot means for moving said part toward and from the nipple as said nozzle is rotated relative to said part.

3. Lubricating apparatus including lubricant-expelling device presenting a barrel and a nozzle presenting an opening in its end to receive lateral projections on a lubricant-receiving nipple, a part inside said nozzle presenting portions engaging the 60 projections when entered in said nozzle to oppose rotation of said part with said nozzle relative to the nipple, and inclined pin and slot means for moving said part toward and from the nipple as said nozzle is rotated 65 relative to said part, said nozzle fixed relative to said barrel.

4. Lubricating apparatus including a lubricant-expelling device presenting a barrel and a nozzle presenting an opening in its 70 end to receive lateral projections on a lubricant-receiving nipple, a part inside said nozzle presenting portions engaging the projections when entered in said nozzle to oppose rotation of said part with said nozzle 75 relative to the nipple, and inclined pin and slot means for moving said part toward and from the nipple as said nozzle is rotated relative to said part, said part reciprocable 80 relative to said barrel.

5. Lubricating apparatus including a lubricant-delivering nozzle presenting means for engagement beneath projections on a lubricant-receiving nipple and a sealing part 90 movable relative to said means toward the nipple to seal the joint around a lubricant-receiving opening in the nipple, a rotary valve part movable with said sealing part, and a slot in the rear face of said sealing 95 part cooperating with said valve part.

In testimony whereof, I have signed my name to this specification.

HOWARD J. MURPHY
